CALCULATING MACHINE

Carl M. Friden, Pleasanton, Calif., assignor to
 Friden Calculating Machine Co., Inc., a corporation of California

Application May 10, 1940, Serial No. 334,366

8 Claims. (Cl. 235—63)

This invention relates to calculating machines of the type having an ordinarily shiftable carriage in which the accumulator and revolutions counter are mounted, and is concerned more particularly with the provision of selective control means therefor whereby the carriage can either be tabulated to one end position or tabulated to the other end position with the combination of a resetting operation of the registers.

It is an object of the invention, therefore, to provide improved selective control means for controlling shifting and resetting operations of a shiftable register.

Another object of the invention is to provide improved shifting and resetting control means whereby the carriage can optionally be tabulated to an end position without a resetting operation or tabulated to another end position coupled with a resetting operation.

Other objects and advantages of the invention will be apparent from the following description of a preferred embodiment thereof, as illustrated in the accompanying drawings, in which:

Figure 1 is a sectional elevational view of a calculating machine embodying the invention, the plane of the view being indicated by the line 1—1 in Figure 3.

Figure 2 is side elevational view of the calculating machine illustrating certain of the control mechanisms with some parts shown in section, the view being taken as indicated by section line 2—2 in Figure 3.

Figure 3 is a plan view of the calculating machine with the carriage and keyboard removed and with certain parts shown schematically.

Figure 4 is a rear elevational view with certain parts shown in section and with the lower part of the view omitted.

Figure 5 is a fragmentary rear elevation similar to Figure 4 but showing the carriage in a different shifted position thereof.

Figure 6 is a fragmentary sectional view taken in a plane indicated by the line 6—6 in Figure 3.

Figure 7 is a fragmentary sectional elevation taken in a plane indicated by the line 7—7 in Figure 3.

My invention is disclosed as embodied in a calculating machine having an actuator of the universal operation continuous drive cycle type. Machines of this type are illustrated in my co-pending applications, Serial No. 724,482, filed May 8, 1934, Serial No. 27,338, filed June 19, 1935, and Serial No. 42,268, filed September 26, 1935.

Generally, the machine comprises a frame and a carriage mounted for endwise shifting move-

ment on the frame. The carriage has mounted therein the registers of the machine comprising the accumulator and the revolutions counter, while the frame provides a support for the various mechanisms for entering values in the registers. The frame includes base 10 (Figure 1) which supports casing 11 and has left and right side frame plates 12 and 13 (Figs. 1 and 3) mounted thereon. Side plates 12 and 13 are connected by various cross frame brackets 16, 17, 18, and 19 which serve to mount various mechanisms referred to hereinafter. Register carriage 22 (Fig. 1) is mounted on frame brackets 16 and 18, as by rollers 23, for endwise shifting movement laterally of the machine in either direction to various ordinal positions as controlled by means described hereinafter.

Register carriage 22 (Fig. 1) includes a carriage frame 24 in which numeral wheels 31 are mounted by numeral wheel shafts 32 journaled in frame 24. To transmit increments of value to the numeral wheels 31, each shaft 32 extends below the carriage frame 24 and has ten tooth numeral wheel gear 33 which is actuated by means described later.

Means are provided in carriage 22 for resetting numeral wheels 31 to zero registration, and such means may include rack bar 36 which cooperates with mutilated gears 37 carried by the numeral wheel shafts 32 in a conventional manner. The rack bar 36 may be actuated by manual means (not shown) or it may be operated by power operated means described hereinafter.

The revolutions counter comprises numeral wheels 41 mounted on numeral wheel shafts 42 and having resetting means associated therewith including the rack bar 43 which is also of conventional construction and cooperates with the mutilated gears 44 on the shafts in the usual manner. If desired, the rack bar 43 may be coupled to the bar 36 of the accumulator as shown in said co-pending application, Serial No. 42,268. Thus, each register in the carriage is provided with zeroizing means shiftable with the carriage, and these zeroizing means are adapted for power operation in a manner later described. The actuating means and the associated driving and value selecting means for the registers will now be described briefly as they are generally similar to those described in said application, Serial No. 724,482.

The values to be introduced into the accumulator numeral wheels are selected by means of a plurality of banks or orders of settable value keys 51, one of which banks is illustrated in part in

Figure 1. Each bank of keys 51 cooperates with selecting mechanism including a pair of parallel spring-urged slides 52 mounted for endwise movement to position gears 53 selected with respect to the stepped teeth of the associated actuating cylinder 54 in accordance with the value of the depressed key. Cylinders 54 are mounted on actuating shafts 57 having suitable bevel gear connections with transverse drive shaft 58 which is suitably journaled in side plates 12 and 13.

Transverse shaft 58 and actuating shafts 57 are driven cyclically from motor 59 (Fig. 1) through clutch 61 (Fig. 7) which is driven by a suitable gearing 62 (Fig. 2) from motor shaft 63. Clutch 61 (Fig. 7) is engaged or disengaged by oscillation of spring-urged clutch dog 64 mounted for rotation with shaft 58 and with respect to driving ratchet 66 which is journaled on shaft 58 and driven by gearing 62. Clutch control lever 67 pivoted on side plate 13 controls engagement or disengagement of the clutch by releasing or engaging the nose of dog 64 in the full cycle position thereof. During rotation of the clutch, clutch control lever 67 and parts associated therewith are maintained in active position by roller 68 carried by clutch control lever 67 and adapted for engagement with the periphery of the clutch, so that clutch control lever 67 can only move to clutch disengaging position in the full cycle position of the parts shown in Figure 7.

Each pair of gears 53 (Fig. 1) is slidably mounted on a square shaft 71 (Fig. 1) suitably journaled in the frame and carrying a plus-minus gear spool 72 which is slidably and nonrotatably mounted on the associated shaft 71 and has opposite bevel gears 73, 74 for cooperation with the associated numeral wheel gear 33. The gears 73, 74 may be moved from their central neutral position shown in Figure 1 by any suitable means, such as the conventional plus and minus keys of the character disclosed in said application, 724,482.

The control of positive or negative registration is effected through strap 75 carried by rockable shaft 76 and the parts are normally maintained in their central neutral position by means of opposed centralizing arms 77 suitably pivoted on the side plate 12 and connected by spring 78 to be urged against stop 79 on plate 12, the upper end of centralizing arms 77 engage the opposite sides of a pin 81 which moves with the plus-minus gears 73 and 74 and strap 75.

Carriage shifting mechanism.—Means are provided for shifting the carriage in either direction from one ordinal position to another by power driven means controlled by manually operable keys.

Carriage 22 (Figs. 1 and 4) has rack 82 mounted along the rear side thereof and the rack 82 is provided with vertical slots 83 formed in the lower edge thereof and spaced apart a distance equal to the ordinal spacing of the machine. Slots 83 are adapted for engagement by opposite shift pins 84 on shift gear 86 which is journaled on frame bracket 16 and is rotated by means described later to effect shifting of the carriage. One-half revolution of the gear 86 effects one ordinal spacing of the carriage. Suitable centralizing arms 87 may be associated with the shift gear 86.

The end slots 83 are formed in part by yieldable pawls 88 and 89 which rock against the respective springs when an attempt is made to shift the carriage past their respective end positions thereof.

In order to rotate the shift gear 86 in either direction by selectively operable drive connections from the actuating means of the machine, the two lowest order actuating shafts 57 (Figs. 1 and 3) are extended rearwardly and have respective collars 91 secured adjacently the ends thereof. Each collar 91 is provided with a slidable tooth and slot connection 92 with a shiftable drive establishing collar 93 mounted on the end of the associated shaft 57. Each collar 93 has a tooth 94 adapted for engagement with the corresponding slot in one of respective gear sleeves 101, 102 which are suitably journaled on the frame. Gear sleeve 101 has gear 103 meshing with idler gear 104 which meshes with shift gear 86. Gear sleeve 102 has gear 106 offset axially from idler gear 104 meshing with wide reverse idler gear 107 suitably journaled on the frame and meshing with idler gear 104. Thus rotation of gear sleeves 101 and 102 in a clockwise direction as viewed in Figure 4 causes shifting of the carriage to the left and to the right respectively as viewed from the front of the machine.

Manually operable control means are provided for the carriage shifting mechanism to enable shifting the carriage in either direction through one or more ordinal spaces. Shift keys 111, 112 (Fig. 2) are depressible to initiate shifting the carriage to the right and left respectively as viewed from the front of the machine. Depression of either key serves to enable the associated drive connection as well as to engage the clutch and energize the motor. Keys 111 and 112 are suitably mounted for endwise movement on the frame plate 13 and carry respective pins 113 associated with lever 114 (Fig. 2) pivoted at 116 on the frame plate. One part of lever 114 has inclined cam slots 115 for cooperation with respective pins 113. Lever 114 is connected by link 117 (Figs. 2 and 7) with the clutch control lever, so that the clutch is engaged upon depression of either shift key. At its lower end, lever 114 (Fig. 2) is pivotally connected with lever 118 also suitably pivoted on the frame and carrying an insulated pin 119 operatively related to close contacts 120 of the motor circuit upon depression of either shift key.

To enable the respective drive connections from the actuating means to the carriage shifting mechanism upon depression of the shift key, the respective pins 113 (Fig. 6) overlie respective levers 121 and 122 secured on shaft 123 and sleeve 124 pivoted on the shaft. Shafts 123 and sleeve 124 carry similar depending arms 126 and 127 respectively (Figs. 3 and 6) having their lower ends disposed in front of respective shift control rods 128 and 129 having springs 131 associated therewith to maintain them normally in inactive position. At their rearward ends, each of rods 128 and 129 carries a fork 132 engaging the associated shiftable collar 93 so that upon depression of either shift key the associated drive connection is established at the same time that the clutch is engaged and the motor is energized. Thus, by selective depression of shift keys 111 and 112, shift gear 86 can be rotated in either direction to effect shifting of the carriage.

Return clear mechanism.—Means are provided whereby the carriage may be shifted to its left hand end position and displaced therefrom and then reset to zero registration after such return. This mechanism is generally of the type disclosed in the co-pending application of Carl M. Friden, Serial No. 42,268, filed September 26,

This mechanism includes a key 141 (Fig. 2) mounted for substantial endwise movement on side plate 13 by means of slot and pin connection 142 and pivotal connection 143 with arm 144. To latch key 141 in depressed position latch slide 146 is slidably mounted on side plate 13 having its nose adapted for cooperation with latching tooth 147 on the key 141. The latch slide 146 is spring urged to active position by spring 148 and may be operated to release the key by operation of bell crank 149 in a manner later described.

Upon depression of key 141, means is brought into play to engage the left-hand shifting mechanism, to energize the motor and to engage the clutch as well as to enable the resetting drive connection as will be described.

Arm 144 is secured on transversely extending shaft 151 suitably journaled on the frame work of the machine. To enable the drive upon depression of key 141, shaft 151 (Fig. 2) carries depending arm 152 having pin 153 overlying the end of lever 154 pivoted at 155 on side plate 13. Lever 154 has upstanding arm 156 disposed for engagement with pin 119 on lever 118 so that when lever 154 is rocked clockwise upon depression of key 141 levers 118 and 116 are operated to engage the clutch and close the motor circuit.

To engage the left-hand shift mechanism upon depression of key 141, shaft 151 (Fig. 1) carries arm 157 having pusher link 158 pivotally secured to the upper end thereof and urged in a clockwise direction by spring 159. Pusher link 158 carries pin 161 which is operatively related to depending arm 162 secured on shaft 123 to cause rocking of shaft 123 upon movement of pusher link 158 to the right as viewed in Figure 1. It will be recalled that shaft 123 carries depending arm 126 for operating the lefthand shift drive connection.

The operation of pusher link 158 upon depression of key 141 also serves to enable the resetting drive connection, and for this purpose end 166 of link 158 is operatively related to the forward end of the resetting control rod 167 which extends rearwardly (Fig. 2) to carry fork 168 for shiftable drive-establishing collar 169 having a drive connection with one of shafts 57 and adapted for engagement with sleeve 171. Sleeve 171 (Fig. 4) carries cam 172 for oscillating arm 173 which is held engaged with the cam by spring 174. Arm 173 has a pin and slot connection with slide 176 mounted for reciprocation on frame bracket 16. Slide 176 has offset tooth 177 for engagement with arm 178 depending from reciprocating actuating slide 179 adapted to operate the rack bars 36 and 43 respectively.

Thus upon depression of key 141, the carriage is first shifted to its left hand position as shown in Figure 4, and when in such position, another cycle of operation follows when actuating slide 176 can become effective to reset the accumulator and the revolutions counter to zero. During the resetting or clear cycle one of shift pins 84 becomes operative to oscillate yieldable pawl 88, whereby its end 181 (Figs. 2 and 4) rocks bell crank 149 to effect release of key 141. End 181 also strikes slide 182 to oscillate bell crank 183 whose lower end is connected by link 184 with arm 186 depending from shaft 187 (Figs. 1 and 2). Shaft 187 (Fig. 1) also carries arm 188 underlying pusher link 158 so that during the last cycle this pusher link is lifted to release the rod 167 so that only one resetting cycle can occur.

Carriage return.—Means are provided whereby

simultaneous manipulations of shift key 111 and return clear key 141 causes return of the carriage to the right while disabling the clearing or resetting function of the key 141. It will be recalled that upon depression of right hand shift key 111, sleeve 124 and arm 127 associated therewith are oscillated to engage the right-hand shift drive connection. Arm 127 (Figs. 2 and 6) is connected by link 191, depending arm 192, pivoted on shaft 151 and having a bail connection 193 with an offset arm 194 underlying pusher link 158. Thus upon depression of key 111 to engage the right-hand shifting mechanism, the offset arm 194 is oscillated to lift pusher link 158 and thereby disable its function with respect to the resetting drive connection and also with respect to the engagement of the left hand shift drive connection.

Thus, even though key 141 is depressed its control over the left-hand shift mechanism and the resetting mechanism is disabled. However, the simultaneous depression of keys 141 and 111 actuates the lever system 114, 118 (Fig. 2) to engage the clutch and close the motor circuit, and because at the same time the right-hand shift drive connection is enabled and will continue until the carriage arrives at its right-hand end position. This continued operation occurs because key 141 is latched in depressed position and serves through the lever system 114, 118, and 116 to also hold key 111 depressed because of the interengagement of pin 113 with the associated cam slot 115.

When the carriage reaches its right-hand end position as shown in Figure 5, pawl 89 is oscillated by one of shift pins 84 to oscillate lever 196 which is pivoted at 197 on rock 82. In the right-hand end position of the carriage, end 198 of lever 196 overlies bell crank 149, so that upon rocking movement of lever 196 bell crank 149 and latch slide 146 (Fig. 2) are operated to release key 141 and also key 111.

I claim:

1. In a calculating machine having a shiftable carriage, a register in said carriage, mechanism for shifting said carriage to a pre-determined position thereof and effecting clearing of said register including a manually operable key, mechanism for shifting said carriage for one or more ordinal positions including a manually operable key, and means responsive to simultaneous depression of both said keys for effecting operation of said last-named mechanism under control of a portion of said first-named mechanism to shift to a second pre-determined position without clearing of said register.

2. In a calculating machine having a shiftable carriage, a register in said carriage, mechanism for shifting said carriage to a pre-determined position thereof and effecting clearing of said register including a manually operable key and means for latching said key in depressed position, mechanism for shifting said carriage for one or more ordinal positions including a manually operable shift key, and means responsive to simultaneous depression of both said keys for effecting operation of said last-named mechanism under control of a portion of said first-named mechanism to shift to a second pre-determined position without clearing of said register, said last-named means including means for holding said shift key in depressed position under control of said latching means.

3. In a calculating machine having a shiftable carriage, a register in said carriage, mechanism

for shifting said carriage in one direction to a predetermined ordinal position thereof and effecting resetting of said register including a manually operable key, mechanism for shifting said carriage in the other direction for one or more ordinal positions including a manually operable key, and means responsive to simultaneous depression of both of said keys for effecting operation of said last-named mechanism under control of a portion of said first-named mechanism to shift the carriage in said other direction to a second pre-determined position without resetting of said register.

4. In a calculating machine having a shiftable carriage, mechanism for shifting said carriage in one direction to a pre-determined ordinal position thereof including a manually operable key, mechanism for shifting said carriage in the other direction for one or more ordinal positions including a manually operable key, and means responsive to simultaneous depression of both of said keys for effecting operation of said last-named mechanism under control of a portion of said first-named mechanism to shift the carriage in said other direction to a second pre-determined position.

5. In a calculating machine having a shiftable carriage, a register in said carriage, mechanism for shifting said carriage in one direction to a predetermined position thereof and for clearing said register while in said position including a manually operable key, and control mechanism for effecting a carriage shifting operation including a second manually operable key, and means responsive to simultaneous depression of both of said keys for disabling said first-named mechanism to eliminate the shifting and clearing functions controlled by said first-named key while enabling carriage shifting under control of said last-named key.

6. In a calculating machine having a shiftable

carriage, means for shifting said carriage selectively in either direction, means including a manually operable key for causing operation of said shifting means to position said carriage in a predetermined position thereof, said operation causing means including an operating connection movable upon depression of said key and having a yieldable normally active element therein, and other means for causing operation of said shifting means including means for moving said yieldable element to inactive position.

7. In a calculating machine having a shiftable carriage, means for shifting said carriage selectively in either direction, two controlling connections for said shifting means, means including a key for operating one of said connections to effect shifting of said carriage to one end position thereof, means including a second key for operating the other of said connections to effect shifting of said carriage for one or more steps of movement, and means responsive to simultaneous depression of said keys for disabling said one connection and for causing operation of said second-named operating means under control of a portion of said first-named operating means to cause shifting of said carriage to the other end position thereof.

8. In a calculating machine having a shiftable carriage, a register in said carriage, mechanism for shifting said carriage to an end position thereof and effecting clearing of said register including a manually operable key, mechanism for shifting said carriage for one or more ordinal positions including a manually operable key, and means responsive to simultaneous depression of both said keys for effecting operation of said last-named mechanism under control of a portion of said first-named mechanism to shift said register to the other end position thereof without clearing of said register.

CARL M. FRIDEN.
